UNITED STATES PATENT OFFICE.

GEORGE L. PHILLIPS, OF NEWKIRK, OKLAHOMA.

DESIGN FOR A BUTTON.

44,024.

Specification for Design.

Patented May 13, 1913.

Application filed March 29, 1913. Serial No. 757,704. Term of patent 14 years.

To all whom it may concern:

Be it known that I, GEORGE L. PHILLIPS, a citizen of the United States, residing at Newkirk, in the county of Kay, in the State of Oklahoma, have invented a new, original, and ornamental Design for Buttons, of which the following is a specification, reference being had to the accompanying drawing, forming a part thereof.

The figure is a front elevation of a button, showing my new design.

I claim:

The ornamental design for a button, as shown.

GEORGE L. PHILLIPS.

Witnesses:

E. J. MORRIS,
D. M. HAMLIN.
